UNITED STATES PATENT OFFICE.

ERNST WIESE, OF BERLIN, GERMANY.

SELF-LIGHTING DEVICE FOR GAS-BURNERS.

SPECIFICATION forming part of Letters Patent No. 633,405, dated September 19, 1899.

Application filed May 24, 1899. Serial No. 718,091. (No model.)

To all whom it may concern

Be it known that I, ERNST WIESE, a citizen of the Empire of Germany, residing at Berlin, in the Kingdom of Prussia, in the Empire of Germany, have invented a new and useful 5 Self-Lighting Device for Gas-Burners and the Like, of which the following is a specification.

The self-lighting devices hitherto known having a piece of spongy platina and applied 10 to the top of the chimney of gas-burners, especially incandescent gas-light burners and the like, have not proved successful, because the spongy platina, though not glowing any more after kindling the flame, yet is very soon 15 spoiled through the combustion products constantly arising, and is thereby rendered unfit for use.

My invention relates to a new self-lighting device; and the objects of my invention are, 20 first, to provide a hole in a cap placed at a certain height above the chimney-top for allowing of the gas passing through and getting at the piece of spongy platina above the hole in order to be thereby lighted, and, secondly, to provide a flap, valve, or clack-valve 25 pivoted at the bottom side of the cap and leaving the hole open until the gas is turned on and lighted and arranged for closing the hole, when being acted upon by the arising 30 combustion products, after the kindling of the flame, so as to lead off the combustion products along the bottom side of the cap to the outside, and thus to keep them off from the spongy platina, which always retains its 35 position at the proper place for kindling the flame. The piece of spongy platina will then last much longer and retain its lighting power.

The new self-lighting device is illustrated in the accompanying drawings, in which— 40 Figure 1 is a vertical section of the device having a conical cap placed above the top edge of the chimney, the clack-valve being shown in the open position. Fig. 2 is a vertical section of the same device, the clack- 45 valve being shown in the closed position. Fig. 3 is a vertical section of a modification of the device in which the cap is made flat and arranged in a slanting position. Fig. 4 is a vertical section of another modification of 50 the device in which the flat cap is placed horizontally above the top edge of the chimney.

Similar letters refer to similar parts throughout the several views.

The conical cap *g* of the device shown in Figs. 1 and 2 has a diameter somewhat larger 55 than that of the chimney *z* and is fixed at a certain height above the top edge of the chimney in some known manner—for example, by a fork *s*, as shown, or several forks, the prongs of which reach over the inside and the outside 60 walls of the chimney. The conical cap *g* may be made of mica or other suitable material and be provided with a hole *l* near the top corner. From a piece of wire *b*, fastened on the cap *g*, is suspended a piece of spongy 65 platina *p*, which points at the center of the hole *l*. At the bottom side of the cap *g* a clack-valve *k* is pivoted at *a*, which is preferably balanced to a certain extent by a counter-weight *r*, arranged on the lever *n* so as to 70 open the hole *l* when the gas is not lighted and to close the hole *l* when acted upon by the combustion products after the kindling of the flame. Thus on turning the gas on the clack-valve *k* is open and allows of the gas going 75 through the hole *l* and passing freely the spongy platina *p*, which will light the gas. After the kindling of the flame the arising combustion products will close the clack-valve *k*, (see Fig. 2,) and hence they will be conducted along the bottom side of the cap *g* to 80 the outside, the spongy platina *p* being now kept out of reach of the hot combustion products.

In the modification of the device shown in 85 Fig. 3 the flat cap *g* is arranged in a slanting position at a certain height above the top edge of the chimney *z*. This cap *g* has its hole *l* in the center, and the piece of spongy platina *p*, suspended from a wire *b* or other support 90 on the upper side of the cap *g*, again points at the center of the hole *l*. The clack-valve *k* may be pivoted at the uppermost point of the cap *g* at *a* and arranged to hang downward in a slanting position when open, as is 95 shown by the dotted lines, so that the gas upon turning the cock on may easily arise in the chimney *z* to the hole *l* and get at the spongy platina *p* to be thereby lighted.

In the device shown in Fig. 4 the cap *g*, arranged horizontally, may be supported by arms *s s*, projecting from a ring *t*, placed on 100

- the top edge of the chimney *z*. The arrangement of the hole *l*, the piece of spongy platina *p*, and the clack-valve *k* are the same as before.
- 5 In general the cap *g*, above the chimney-top, may be shaped in some suitable style and according to the circumstances without deviating from the principle of my invention. It may be conical, tunnel-like, cup-like, even, 10 and so on. As to the clack-valve, flap, or valve *k* the counterweight *r* is preferably made adjustable, so as to balance the valve or flap to a nicety. For the valve or flap *k*, the shape of which may be of any kind, it is 15 essential that it should be acted upon by the arising hot combustion products in such a manner as to close the hole *l* under the piece of spongy platina *p* and lead off the gases. The manner of operating the valve or flap *k* may 20 also be altered to suit the circumstances. It is only necessary to so arrange the device that after the kindling of the gas the combustion products are kept off from the spongy platina.
- 25 What I claim as my invention, and desire to secure by Letters Patent, is—
1. In a self-lighting device for gas-burners and the like, the combination with a cap having a hole, of a piece of spongy platina above said hole, and a valve opening and closing 30 said hole, substantially as set forth.
2. In a self-lighting device for gas-burners and the like, the combination with a cap made of mica and having a hole, of a piece of spongy platina held by suitable means above said 35 hole, and a valve opening and closing said hole, substantially as set forth.
3. In a self-lighting device for gas-burners and the like, the combination with a cap having a hole and arranged at a certain height 40 above the top edge of the chimney, of a piece of spongy platina suspended above said hole, and a valve arranged at the bottom side of said cap for opening said hole, when gas is turned off, and for closing said hole, when being 45 acted upon by the arising combustion products after the lighting of the gas, substantially as set forth.
4. The combination with a gas-lamp chimney, of a cap arranged at a certain height 50 above the top of same and having a hole, a piece of spongy platina held above said hole, and a valve opening and closing said hole from below, substantially as set forth.
5. In a self-lighting device for gas-burners 55 and the like, the combination with a cap having a hole, of means for holding said cap at certain height above the chimney-top, a piece of spongy platina held above the hole of said cap, and a valve arranged at the bottom side 60 of said cap to open said hole for allowing the gas turned on to pass and get at the spongy platina to be thereby lighted, the said valve being arranged to be acted upon by the arising combustion products for closing said hole, 65 so that the combustion products are led off to the outside, and kept off from the spongy platina, substantially as set forth.
6. In a self-lighting device for gas-burners and the like, the combination with a cap having a hole, of an arm projecting from the top 70 edge of the chimney and holding said cap at a certain height above the chimney-top, a piece of spongy platina suspended above the hole of the cap from some support attached to the latter, and a valve arranged at the bottom side of said cap to open said hole for allowing the gas turned on to pass and get at the spongy platina to be thereby lighted, the said valve being arranged to be acted upon by the arising combustion products for closing said 75 hole, as that the combustion products are led off to the outside and kept off from the spongy platina, substantially as set forth.
7. In a self-lighting device for gas-burners and the like, the combination with a cap having a hole, of a plurality of arms projecting from the top edge of the chimney and holding said cap at a certain height above the chimney-top, a piece of spongy platina suspended above the hole of the cap from some 80 support attached to the latter, and a valve arranged at the bottom side of said cap to open said hole for allowing the gas turned on to pass and get at the spongy platina to be thereby lighted, the said valve being arranged to be acted upon by the arising combustion products for closing said 85 hole, so that the combustion products are led off to the outside and kept off from the spongy platina, substantially as set forth.
8. In a self-lighting device for gas-burners and the like, the combination with a cap of suitable shape supported by suitable means at a certain height above the top edge of the chimney and having a hole, of a piece of 90 spongy platina held by suitable means above said hole, and a clack-valve pivoted at said cap for opening and closing said hole from below, substantially as set forth.
9. In a self-lighting device for gas-burners and the like, the combination with a cap of suitable shape and having a hole, of means for holding said cap at a certain height above the chimney-top, a piece of spongy platina held by a wire above the hole of said cap, a 95 clack-valve pivoted at said cap for opening and closing said hole from below, and a counterweight attached to said clack-valve, substantially as set forth.
10. In a self-lighting device for gas-burners 100 and the like, the combination with a cap of suitable shape and having a hole, of means for holding said cap at a certain height above the chimney-top, a piece of spongy platina held by a wire above the hole of said cap, a 105 clack-valve pivoted at said cap for opening and closing said hole from below, and an adjustable counterweight attached to said clack-valve for balancing the same to such an extent, that the valve opens the hole until the 110 gas turned on and passing through the hole gets at the spongy platina and is thereby lighted, whereupon the valve is acted upon by the arising combustion products and closes 115

the hole, so that the combustion products are led off to the outside and kept off from the spongy platina, substantially as set forth.

11. In a gas-lighting device, a perforated cap adapted to be supported on a gas-burner chimney, an automatically-actuated valve for the perforation in the cap, and means for

supporting platina-sponge above the perforation in the cap, substantially as set forth.
